UNITED STATES PATENT OFFICE.

CAMILLO BRUUN, OF CHICAGO, ILLINOIS.

MUSTACHE-GUARD.

SPECIFICATION forming part of Letters Patent No. 553,836, dated February 4, 1896.

Application filed September 19, 1894. Serial No. 523,520. (No model.)

To all whom it may concern:

Be it known that I, CAMILLO BRUUN, a citizen of the United States, residing at Chicago, in the county of Cook and State of Illinois, 5 have invented certain new and useful Improvements in Mustache-Guards; and I do hereby declare the following to be a full, clear, and exact description of the invention, such as will enable others skilled in the art to which 10 it appertains to make and use the same.

This invention relates to a novel construction in a mustache-guard for cups, glasses, and the like; and it consists in the features of construction hereinafter fully described 15 and specifically claimed.

In the accompanying drawings, Figure 1 is a perspective view of a cup having a mustache-guard constructed in accordance with my invention applied thereto. Fig. 2 is a 20 rear elevation of a mustache-guard. Fig. 3 is a sectional view of the same on the line 3 3 of Fig. 2. Fig. 4 is a top plan.

Referring now to said drawings, 1 indicates the holding-plate of the guard, which is curved 25 to conform to the contour of a cup or drinking-glass. The said plate 1 is provided along its upper edge with an inwardly-turned flange 2, parallel with the plate and located a little distance therefrom, the space or groove 3 be- 30 tween the plate and flange corresponding to the thickness of the edge of the drinking-glass. Secured to the flange 2 and a little distance below its upper edge is the guard 4, in which an opening 5 is made adjacent to the 35 flange and about midway between its ends.

From the foregoing description it will be seen that this mustache-guard can be easily applied or removed from a drinking-glass, and will be firmly held thereon by reason of the engagement of the edge of the glass be- 40 tween the plate 1 and flange 2. In use the guard 4 effectually prevents the mustache from contact with the liquid in the glass, while the opening 5 permits the passage of the liquid.

45

In making a mustache-guard of this construction I prefer to stamp the entire article from one piece, as shown, and in this case the flange 2 will consist of two thicknesses of the sheet metal lying flat against each other, 50 as clearly shown in Figs. 2 and 3.

I claim as my invention—

A mustache-guard consisting of a curved plate to fit the exterior of a glass or mug and having an inwardly and downwardly turned 55 flange at its upper edge providing a space between said plate and flange to receive the edge of a glass or mug, and said flange being bent upon itself and then inwardly to form a guard approximately at a right angle to said 60 plate, and an opening in said guard approximately midway between the ends of the same and adjacent said flange, substantially as described.

In testimony whereof I affix my signature 65 in presence of two witnesses.

CAMILLO BRUUN.
